United States Patent Office

Des. 202,799
Patented Nov. 9, 1965

202,799

KNIFE SHARPENER

Don J. De Fano, River Grove, and Robert I. Kallman,
Geneva, Ill., assignors of one-half to Cory Corporation,
a corporation of Delaware, and one-half to G-M
Laboratories, Inc., a corporation of Illinois

Filed June 30, 1964, Ser. No. 80,640

Term of patent 14 years

(Cl. D37—1)

FIG. 3.

FIG. 4.

FIG. 5.

FIGURE 1 is a front perspective view of a knife sharpener, showing our new design;

FIGURE 2 is a rear perspective view thereof;

FIGURE 3 is a top plan view thereof;

FIGURE 4 is a front elevational view thereof; and

FIGURE 5 is a right end elevational view thereof.

The dominant features of our design reside in the portions shown in full lines.

We claim:

The ornamental design for a knife sharpener, substantially as shown and described.
